EDWARD P. FORBES, OF DORCHESTER, MASSACHUSETTS, ASSIGNOR OF ONE-EIGHTH TO
WILLIAM H. MCKENNEY AND ONE-EIGHTH TO ALMA R. MCKENNEY, BOTH OF TAUN-
TON, MASSACHUSETTS

SHEET METAL LOCK

Application filed November 2, 1931. Serial No. 572,594.

This invention relates chiefly to a lock adapted to secure the flap of an envelope to the back thereof in such manner that the flap cannot be separated from the back without mutilating the lock and thereby indicating that the envelope has been opened.

The object is to provide a simple and effective lock of compact form and composed entirely of two sheet metal parts or members one constituting a socket and the other a stud, each made from a single piece of sheet metal.

Of the accompanying drawing forming a part of this specification,—

Figures 1 and 2 show in perspective the parts or members of my improved lock separated from each other, substantially the preferred size of said members being shown by these figures.

Figure 3 shows the lock in section on a larger scale.

Figure 4 is an enlargement of a portion of Figure 3.

The same reference characters indicate the same parts in all of the figures.

One of the two members of the lock includes a socket having a cylindrical wall 12, a head closing one end of the wall, an inwardly projecting annular rib 14 contracting the opposite end of the wall, and a base flange 15 provided with attaching means, all formed from a single piece of sheet metal. The rib 14 is a folded zone of the socket wall as best shown by Figure 4.

The other member is a stud having a low cylindrical wall 16, a head 17 closing an end of said wall, and a base flange 18 having attaching means, all formed from a single piece of sheet metal.

The stud wall 16 is cut to define a plurality of integral outwardly inclined resilient struts 19 preferably three in number, joined at the inner ends to the head 17.

The stud is formed to enter the socket and the struts 19 are adapted to be sprung inwardly by the rib during the insertion of the stud into the socket until their free ends pass across the rib 14, and then to spring outwardly so that their outer ends engage the rib 14, and also engage or bear on the inner surface of the socket wall 12 as shown by

Figure 3. The struts are thus caused to lock the socket to the stud at a plurality of points, the struts being covered and guarded by the socket so that they cannot be disengaged from the rib without mutilation.

The base flanges 15 and 18 may be provided with integral means whereby they are adapted to be attached respectively to the flap 21 and back 22 of an envelope, said means being preferably embodied in spurs 23 formed on the flange 15, and spurs 24 formed on the flange 18.

It will be seen that the forms shown by the drawing may be imparted by automatic means to sheet metal blanks, the blank for the socket including metal for the wall 12, the head 13, the annular rib 14, and the spurs 20, while the blank for the stud includes metal for the wall 16, the head 17, the struts 19 and the spurs 24.

When the lock is intended for use on an envelope the preferred height of the socket wall 12 is about three thirty seconds of an inch, so that the socket head does not project objectionably from an envelope to which the socket is attached. This minimum projection is feasible because of the sheet metal construction. The sheet metal of the member which includes the stud is preferably sheet steel to provide suitably resilient struts. The sheet metal of the member which includes the socket is not necessarily of high resilience, and is preferably rustless metal such as sheet brass. This metal is adapted to have an ornamental finish and is sufficiently ductile to enable the folded rib to be formed without cracking the metal.

It is obvious that the use of the described lock is not necessarily limited to envelopes.

I claim:

1. A lock of the character stated composed of two members each made wholly from a single piece of sheet metal, one member including a socket having a cylindrical wall, a head closing one end of the wall, an inwardly projecting annular rib contracting the opposite end of the wall, and a base flange surrounding the rib and having attaching means, the other member including a stud having a cylindrical wall, a head closing one end of the wall, resilient struts inclined out-

wardly from the wall, and a base flange surrounding the opposite end of the wall and having attaching means, the stud and struts being insertable through the rib into the socket, and the struts being adapted to spring outward into engagement with the rib at a plurality of points, each strut being joined at its inner end to the stud head and bearing at its opposite end on the socket wall so that the engagement of the struts with the rib and socket wall so connect the stud with the socket that said parts are inseparable without mutilation.

10 2. A lock as specified by claim 1, the said rib being a folded zone of the socket wall.

15 3. A lock as specified by claim 1, the sheet metal of the member which includes the stud being relatively resilient, and the sheet metal of the member which includes the socket being relatively ductile, rustless, and adapted to have an ornamental finish.

20 In testimony whereof I have affixed my signature.

EDWARD P. FORBES.
